UNITED STATES PATENT OFFICE.

ALEXANDER B. LEITH, OF CHICAGO, ILLINOIS.

PERAMBULATOR.

1,347,169.

Specification of Letters Patent. Patented July 20, 1920.

Application filed December 28, 1918. Serial No. 268,650.

To all whom it may concern:

Be it known that I, ALEXANDER B. LEITH, a citizen of the United States, residing at Chicago, in the county of Cook and State 5 of Illinois, have invented a new and useful Improvement in Perambulators, of which the following is a specification.

This invention relates particularly to perambulators, or go-carts; and the primary 10 object is to provide a simple and durable construction, eliminating, as far as possible, the use of steel.

The invention is illustrated, in its preferred embodiment, in the accompanying 15 drawings, in which—

Figure 1 represents a side elevational view of a perambulator constructed in accordance with the invention, one pair of wheels being removed from the axles; and 20 Fig. 2, a horizontal sectional view taken as indicated at line 2 of Fig. 1.

In the construction illustrated, A represents a running gear-frame; B, a seat mounted thereon; C, a folding back mounted on the seat; and D, a folding superstructure mounted on the running gear-frame, and comprising, as a part thereof, a folding handle D¹.

In the preferred construction, the running 30 gear-frame A comprises a pair of longitudinal wooden side-members A¹; front and rear Y-form axle-supports A² and A³, respectively, rigidly connected with each side-member; axles A⁴ carried by the lower ends 35 of the brackets, or supports; and wheels A⁵ journaled on the extremities of the axles. The side-members A¹ are cross-connected by a rear bar A⁶ and an intermediate bar A⁷, which serve to support springs B¹ upon 40 which the seat B is mounted.

Each front axle-support, or bracket, A², comprises a forwardly and downwardly-inclined bar 1 and a rearwardly and downwardly-inclined bar 2, which are joined together near their lower ends, thus affording 45 a bracket of general Y-form. The member 1 has an upper extension 1^a which projects above the corresponding side-member A¹ of the frame and serves to support one of the 50 pivots for the folding superstructure D; and the member 1 has a lower extension b which projects below the member 2 and serves to support the axle A⁴. The member 2 has an upward extension 2^a which projects

above the side-member A¹; and the lower 55 extremity 2^b of the member 2 crosses the member 1 a short distance above the axle. The members 1 and 2 are disposed inside of the side-member A¹. At the points where the members 1 and 2 cross the side-members 60 A¹, the members 1 and 2 are recessed at their outer sides to receive the member A¹, and the member A¹ is recessed at its inner side to receive the members 1 and 2. In other words, the members are mortised together; 65 and a secure connection is effected by means of bolts 3. In a corresponding manner, the members 1 and 2, where they cross each other, are recessed at their adjacent sides and fitted together by suitable mortising; 70 and a secure connection is afforded by means of a bolt 4. The members 1 and 2 comprise wooden bars; and the lower extension b of the members 1 are provided with perforations to receive the axle A⁴. The extensions 75 b are also provided with slits 5, thus producing forked extremities; and these forks are connected by clamping bolts 6, which serve to clamp the extensions b upon the axle. In other words, the extensions b comprise split ends equipped with clamping bolts, so that the axle may be firmly secured 80 by means of this simple expedient.

The upward extensions 2^a of the members 2 are connected by a cross-bar 7, which may 85 comprise a round of wood, secured between the extensions 2^a by means of screws 8, as shown in Fig. 2. A foot-supporting pocket 9 is formed by connecting a ply of fabric, or leather, with the bar 7 and the front portion of the seat B.

Each rear axle support A³ comprises a forwardly and downwardly-inclined bar 10 having an upward extension 10^a projecting above the side-member A¹ and affording a 95 support for the handle-pivot; and a rearwardly and downwardly-inclined member 11 having the upper end secured, by a bolt 11^a, to the side-member A¹ and having a lower extension 11^b projecting below the member 10 and affording a support for the rear axle 100 A⁴. The members 10 and 11 are disposed in the side of the side-member A¹ and have mortised connection therewith, in a manner described with reference to the front axle-supports. The members 10 are firmly secured to the members A¹ by means of bolts 105 10^b. At the point where the members 10 and

11 cross each other, they are mortised on their adjacent sides and are secured together by means of a bolt 12. The lower extensions 11^b are provided with perforations to receive 5 the axle A⁴, and these extensions are also split and equipped with clamping bolts 13.

The seat B may be mounted on the running gear-frame through the medium of any suitable springs. In the illustration given, 10 the springs B' are of leaf-form and provided with loops to give the desired resiliency, the extremities of the springs being secured to the cross-bars A⁶ and A⁷ of the running gear-frame, and the intermediate portions 15 14 of the springs having the seat B mounted thereon.

The back C of the seat is connected by 20 hinges 15 at the rear portion of the seat and adapted to fold forwardly upon the seat. The seat is adapted to be supported in different 25 positions of inclination by means of adjustable blocks 16, which are mounted upon rearward extensions 16^a of the seat-frame. The means for adjusting is not shown in detail, as this feature is unimportant in connection with the present application.

The folding superstructure D comprises the handle D¹ whose side-members, or arms, have their lower end-portions connected, by 30 pivots 17, with the upward extensions 10^a of the members 10; a pair of links 18 having their lower ends connected, by pivots 19, with the upward extensions 1^a of the members 1; and links, or bars, 20, having their front ends 35 connected, by pivots 20^a, with the upper ends of the links 18, and having their rear ends connected, by pivots 20^b, with the intermediate portions of the handle-bars D¹. The handle-bars have extensions 21 below the 40 pivots 17, which are adapted to bear against stops 22, with which the rear portions of the side-members A¹ of the running gear are equipped. The superstructure D is adapted to be held in the extended position by means 45 of folding brace-links 23, in a well-known manner. The links 18 and 20, as well as the handle-bars D¹, may be of wood. Preferably, the folding braces 23 comprise metal bars connected by short links, or joint-members, 23^a.

From the description given, it will be understood that the structure is chiefly of wood. Aside from the springs, axles, and locking braces, only a few metal parts, such as 55 screws, bolts and hinges, are required.

The construction described is strong, durable, inexpensive, and of pleasing appearance. The structure is also very light. When desired, the wheels may be removed, 60 and the superstructure may be folded upon the running gear-frame for convenience in shipping. Also, the structure is of the semi-folding type, which facilitates the use of the device in traveling.

55 The foregoing detailed description has

been given for clearness of understanding only, and no unnecessary limitation should be understood therefrom, but the appended claims should be construed as broadly as 70 permissible, in view of the prior art.

What I regard as new, and desire to secure by Letters Patent, is:

1. In a perambulator, a running gear-frame comprising wooden side-bars, Y-form wooden axle-supports, each having upwardly divergent arms rigidly connected with the corresponding side-member of the frame, one of said bars having a downward extension affording an axle-support, axles carried by said axle-supports, and cross-members connecting the side-members of the running gear-frame. 75

2. In a perambulator, the combination of a running gear-frame comprising a pair of longitudinal side-bars, Y-form axle-supports 80 each having upwardly divergent arms rigidly secured to the corresponding side-member, one arm of each axle-support having an extension projecting above the side member, and cross-members connecting said side-members; a seat mounted on the running gear-frame; and a folding superstructure mounted on the running gear-frame comprising a handle having arms pivotally connected with the upward extensions of the 85 rear axle-supports; links having their lower ends pivotally connected with the upward extensions of the front axle-supports, and links connecting the upper ends of said last-named links with intermediate portions of 90 the handle-bars. 95

3. In a perambulator, the combination of a running gear-frame comprising longitudinal side-bars, a front Y-form axle-support having upwardly-divergent arms rigidly 105 connected with the front portion of each side-member, one arm of each of said supports having a downward extension affording an axle-support, and both arms of each of said supports having an upward extension 110 projecting above the side-member of the frame, a rear Y-form axle-support having upwardly divergent arms rigidly connected with the rear portion of each side-member, one arm of each of said rear axle-supports 115 having a downward extension affording an axle-support, and one arm having an upward extension adapted to support a handle-pivot; cross-bars connecting said side-members; a seat mounted on said running gear-frame; a flexible foot-supporting pocket connected with the upward extensions of the front arms of the front axle-supports, and a folding superstructure comprising handle-bars pivotally connected with the upward 120 extensions of the rear axle-supports, a pair of links pivotally connected with the upward extensions of the rear arms of the front axle-supports, and a pair of links 125 pivotally connected with the upper ends of 130

said last-named links and pivotally connected with the intermediate portions of the handle-bars.

4. In a perambulator, a running gear-frame comprising a pair of longitudinal wooden bars and axle-supporting brackets connected therewith, each comprising a pair of mutually bracing wooden bars having their upper ends in mortised and bolted connection with said side-bars and having their lower portions crossing each other and mortised and bolted together, one arm of each set having a split extension provided with

an axle-receiving perforation and equipped with a clamping bolt. 15

5. In a perambulator, the combination of a running gear-frame comprising side-bars and cross-bars connecting the same; springs secured to said cross-bars and having loop-20 portions at their front and rear ends depending beneath the side-bars; and a seat disposed above the plane of said side-bars and having its intermediate portion mounted on said springs between the loops in the space between said cross-bars.

ALEXANDER B. LEITH.
